UNITED STATES PATENT OFFICE.

EMANUEL EINSTEIN, OF NEW YORK, N. Y.

DESIGN FOR NAP-SURFACE OF CLOTH.

SPECIFICATION forming part of Design No. 12,953, dated May 30, 1882.

Application filed February 2, 1882. Term of patent 3½ years.

To all whom it may concern:

Be it known that I, EMANUEL EINSTEIN, of the city, county, and State of New York, have originated a novel Design for the Nap-Surface 5 of Cloth, of which the following, in connection with the accompanying drawing, is a full, clear, and exact description.

This design is of that class on which several 10 patents were previously issued to me, dated June 7 and December 27, 1881, in which the general extent or field of the nap is finished smooth, or nearly so, while figured effects are produced on this field of smooth nap by positive lines, grooves, or depressions cut into the 15 pile or nap in the act of shearing the same; and my present design consists in a special form and arrangement of such grooves or depressions by which a novel figured effect is obtained, as hereinafter set forth.

20 In the drawing annexed the figure presents a face view of a piece of napped cloth figured according to my design.

In this design the field or ground consists, as usual, of plain or smooth finished nap, which 25 is indented with a series of continuous longitudinal lines or grooves, *a a*, so as to divide the ground into stripes of nap standing in relief. The grooves *a a* are preferably so spaced as to form alternately wide and narrow stripes *b c* of 30 nap, as illustrated; but this is not essential. Alternating, however, with the continuous lines or grooves *a* are parallel lines of dots or dotted lines *d d*, formed by positive indentations cut into the nap in the act of shearing, as is the 35 case with the continuous grooves *a*, as illustrated in the drawing. I prefer to use two lines of the dots together and to cut them on the

broad bands *b* of the nap, while the narrow bands *c* of nap between the continuous grooves *a* are preferably left plain, as illustrated; but 40 these particular arrangements to alternate number of lines are not essential, although they give a more diverse and ornate character to the design. This design, however, consists essentially in the combination of the lines of dots or 45 indentures *d* with the continuous lines or grooves *a*, which, with the positive stripes of nap made apparent by the grooves, impart a very good effect to the surface of the cloth.

I prefer that the dots or indentations forming the dotted lines *d* be of a rectangular form, 50 as illustrated; but this is not essential to the general effect of the design.

I have described this design as being produced by cutting grooves or indentations into 55 the nap, as this is much preferable; but it is obvious that the design is not necessarily limited to this mode of production.

What I claim is—

1. The specified design for the surface of 60 cloth, consisting of bands or stripes of continuous lines or grooves alternating with bands or stripes of dotted lines or lines of dots, substantially as herein set forth.

2. The illustrated design for the surface of 65 cloth, consisting of continuous parallel grooves spaced to form alternately wide and narrow stripes of nap between them, with lines of dots or indentations traversing the wide bands, substantially as herein described and shown.

EMANUEL EINSTEIN.
